UNITED STATES PATENT OFFICE.

VICTOR QUAEDVLIEG, OF KEREMEOS, BRITISH COLUMBIA, CANADA.

PROCESS AND APPARATUS FOR TANNING HIDES.

1,280,544.

Specification of Letters Patent.

Patented Oct. 1, 1918.

Application filed September 18, 1916. Serial No. 120,733.

To all whom it may concern:

Be it known that I, VICTOR QUAEDVLIEG, a subject of Holland, residing in Keremeos, British Columbia, Canada, have invented a 5 certain new and useful Process and Apparatus for Tanning Hides, of which the following is a specification.

My invention relates to a system of tanning, and one of its objects is the provision 10 of a process by which the hides or skins of animals to be tanned are rendered more porous and more permeable to the tanning solution than in processes of tanning heretofore employed in practice.

15 A further object of the invention is to provide a process for tanning hides and the like, in which the hides are rendered permeable to the tanning solution by uniform bending thereof and without undue or abrupt bending in any portion thereof.

Another object of my invention is the provision of a process by which the hides are alternately bent back upon themselves without undue or abrupt bending but with 25 uniform bending.

A further object of my invention is the provision of apparatus for carrying out the foregoing process, and more particularly for securing automatic uniform bending of the 35 hides in reverse direction while immersed in the tanning solution.

Other objects of the invention will appear hereinafter, the novel features and combinations being set forth in the appended claims.

Referring to the accompanying drawings, Figure 1 represents an end sectional elevation of a vat containing tanning solution in which is immersed a plurality of hides 40 suspended at intervals from a rotatable drum;

Fig. 2 illustrates diagrammatically the outline of an entire untrimmed hide which is particularly adapted for sole leather;

45 Fig. 3 is a plan view of the tanning solution vat, the rotatable drum and the automatic means for operating said drum;

Fig. 4 is a plan view, somewhat diagrammatic, of a plurality of drums mounted on

a single shaft and arranged longitudinally 50 of a series of vats containing tanning solution;

Fig. 5 is a plan view, somewhat diagrammatic, of a series of rotatable drums arranged in parallel in a single vat containing 55 tanning solution;

Fig. 6 is a detail view of mechanism for suspending the hides from the rotatable drum; and

Fig. 7 is a detail view of the means for 60 fastening the suspending devices to the cheeks of the hide shown in Fig. 2.

In Fig. 1, 8 designates a vat for containing a tanning solution 9 preferably to approximately the depth indicated by the 65 transverse horizontal line 10. Mounted in the vat 8 is a drum 11 which may be of any desired material, although I prefer for at least the exterior surface such wood as will withstand the tanning solution employed. 70 If desired, the inner portion 12 which is mounted on the shaft 13 may be made of copper and such other material as will not be attacked by the tanning solution when submerged therein. If a metal drum 12 is 75 employed I still prefer to cover the same with a cylinder 14 composed of suitable wood, although, if desired, the entire rotatable drum may be made of metal open or closed at its end.

80 At intervals around the cylindrical surface of the drum 11 I provide devices to which the hides 21 may be connected. In the present instance these devices each consists of screw-eyes 16 secured to the drum, 85 as shown in Fig. 6. Interlinking with the screw-eyes are links 17 perforated at their lower ends at 18. Inverted U-shaped slits 19 are cut into the butt ends 15 of the hides, as shown in Fig. 2, and after the links 17 90 are inserted through the slits 19 cotter pins 20 are inserted through the perforations 18, as shown in Fig. 7, so as to suspend the hides from the cylindrical surface of the drum 11, as shown in Fig. 1. The hides 21 are therefore suspended in planes extending longitudinally of the axis of the drum 11.

95 In Fig. 1 I have shown a series of 25

spaced apart and circumferentially arranged suspending devices but the number may be varied as desired, but the proportion of the diameter of the drum with respect to 5 the interior width of the vat should be such as to allow plenty of room for free upward and downward movement of the hides between the interior vertical walls of the vat and the lateral surfaces of the drum 11. As 10 shown in Fig. 3, there are in the present instance five series of circumferentially arranged suspending devices, the latter being in horizontal alinement and spaced apart longitudinally approximately the distance 15 between the slits 19 and the butt ends of the hides. In Fig. 3 I have shown 5 circumferential series of suspending devices so as to uniformly distribute the suspending strain 20 on the hides. I prefer to connect the suspending devices to the butt ends of the hides not only to secure more uniform distribution of the suspending strain but also to minimize waste due to the perforations 19 and to secure greater bending of the denser portions 25 of the hides during the operation of the tanning thereof.

In order to regulate the temperature of the tanning solution, heating or cooling devices 22 at or near the bottom of the vat 8 30 may be provided, the heating or cooling devices being connected by means of watertight joints at 23 and 24 to the vat 8.

Referring now to Fig. 3 I will describe the automatic mechanism for rotating the 35 drum alternately in opposite directions. Preferably the drum 11 is rotated about six times in one direction and then automatically reversed and rotated about six times in the opposite direction and so on, the operation 40 being carried on automatically until the power is cut off. The drum shaft 13 is preferably mounted in the bearings 25 and 26, the one designated 25 being inside of the vat 8, as shown in Fig. 3. Keyed to the 45 shaft 13 are two pulleys 27 and 28 between which is mounted a loose pulley 29. A belt 30 is shown in Fig. 3 connecting the loose pulley 29 with the driving pulley 31 which has a length approximately equal to the 50 combined widths of the pulleys 27, 28 and 29 including the intervening spaces. Between the pulley 27 and the driving pulley 31 is a reverse belt 32. An engine may be connected by a belt to the large pulley 33, 55 which is mounted on the driving shaft 34, the latter being supported in the bearings 35, 36 and 37. The driving pulley 33 is mounted on one end of the shaft 34 and on the other end thereof is located a pulley 38 60 connected by the belt 39 to a pulley 40 on a countershaft 41. The latter is mounted in suitable bearings and is provided intermediate its ends with a worm 42 which meshes with a worm gear 43 pivotally mounted and

carrying a suitable cam 44 engaging a pin 65 45 to move the lever 46 on its fulcrum 47 and thereby oscillate the belt shifter 48. After the drum 11 has been given approximately six revolutions the cam 44 will automatically shift the belts 32 and 30 to the 70 right in the position shown in Fig. 3. The reverse belt 32 will then run on the loose pulley 29 and the straight belt 30 will run on the pulley 28 to cause the drum 11 to rotate in the opposite direction. The drum 29 75 is of sufficient width to permit both belts 30 and 32 to run thereon when the power is cut off at the time the belt shifter is in its intermediate position. However, the drum 11 may be stopped in any position desired 80 by cutting off the power from the driving pulley 33.

As illustrated in Fig. 1, when the drum 11 is rotated the suspended hides will be wrapped around the drum so as to overlap 85 each other in series the bending being gradual and uniform and free from abrupt bending or kinks tending to injure the hides or the leather. When the rotation of the drum 11 is reversed not only are the hides 21 at 90 the lower left hand portion of Fig. 1 wrapped around the drum in overlapping formation but the hides on the other side are also wrapped around the drum but now in reverse direction. An important feature of 95 my invention is the process of reverse bending of the hides or the bending thereof in opposite directions so as to work the tanning solution thoroughly into the pores and interstices of the hide and thereby assuring 100 thorough and uniform tanning of the hides into leather and thereby bettering its quality. The reverse bending opens the pores and the overlapping forces the solution into the pores. 105

In Fig. 4 I have represented a series of drums 11' mounted on a single shaft 13' which is supported in bearings 49, 50, 51, 52, 53 and 54, the intermediate bearings 49 to 110 52 inclusive being supported respectively by the cross pieces 55, 56, 57 and 58 in the vat 8'. The hides are suspended by means of a plurality of spaced-apart suspending devices arranged longitudinally of the drums in alinement with each other and also arranged circumferentially as shown in Fig. 1. It will therefore be seen that in Fig. 4 five 115 hides can be arranged in longitudinal planes parallel to the axis of the series of drums.

In Fig. 5 I have shown a series of drums 11'' arranged in parallel in a vat 8''. The transverse shafts 13'' are mounted in suitable bearings in the vat 8'' and connected by the gearing 59 to the belt pulley reversing mechanism comprising the pulleys 28 125 and 29. The hides are connected to the drums 11'' in the same manner as in the construction shown in Figs. 1 and 3. The

spacing between the drums shown in Fig. 5 may be substantially the same as between the end drums and the interior end walls of the vat because the gearing may be such that 5 the drums are each rotated in the same direction and therefore each lifting up the hides on corresponding sides. For instance, as shown in Fig. 1 if the drums are rotated clock-wise each will be lifting the hides and 10 causing them to take up the space to the left of each drum and taking the hides away from the right hand side of each drum. In Fig. 5 the gearing is such that when the 15 drums are rotated in a certain direction the rotation is the same for each drum; this is also true for the reverse rotation of the drum.

Having fully described the principle of my invention and apparatus by means of 20 which my improved process may be carried out, what I claim and desire to have protected by Letters Patent of the United States is—

1. A process of tanning hides consisting in 25 suspending a hide by one end in a substantially vertical plane while completely immersed in tanning solution, and in gradually and uniformly bending the entire hide less than a circle and without wrapping it 30 on itself or over itself, first in one direction and then bringing it back to its substantially vertical plane and gradually and uniformly bending it over all in the opposite direction less than a circle and repeating such steps 35 during the tanning operation and while always immersed in such tanning solution.

2. A process of tanning hides consisting in bending the entire hide semi-cylindrically and uniformly in a tanning solution alter- 40 nately in opposite directions without wrap- 90 ping such hide over itself and without per- 95 mitting any portion of said hide to come in contact with any other portion thereof.

3. A process of tanning hides consisting 45 in suspending a hide from a large drum in a tanning solution and rotating said drum alternately in opposite directions to effect gradual and uniform bending of the whole 50 hide without wrapping it over itself in a circle and without permitting any portion 95 thereof to contact with any other portion thereof and to secure bending of said hide in such manner in said tanning solution back and forth in opposite directions.

55 4. A process of tanning hides consisting in suspending several hides in parallel relation from the exterior of a large rotatable drum in a tanning solution, and operating said drum to alternately bend said hides 60 gradually and uniformly in opposite direc- 100 tions and without permitting any one of said hides to bend back upon itself or over itself.

5. A process of tanning hides consisting

in suspending several hides from a large 65 rotatable drum and rotating said drum alternately in opposite directions to secure gradual and uniform bending of said hides over each other and on the exterior of said drum to secure thorough working of said 70 hides in said tanning solution and uniform pressure of overlapping hides while prevent- 75 ing each hide from being bent back upon itself or over itself and causing each hide to be alternately lifted and lowered on oppo- 75 site sides of said drum.

6. A process of tanning hides consisting in suspending from the exterior surface of a comparatively large drum mounted on a generally horizontal axis several hides in 80 spaced-apart relation and so as to be wholly immersed together with said drum in a tanning solution, and rotating said drum to effect gradual and uniform bending of the 85 hides alternately in opposite directions with- 90 out permitting any one hide to be bent back over itself and without permitting any portion of any one hide to come in contact with any other portion of the same hide.

7. A process of tanning hides consisting in bending several hides alternately all in 95 one direction and all in the opposite direc- 100 tion to cause gradual and uniform bending of each hide to open the pores on both sur- 105 faces and causing the hides to overlap and press against one another to force the tan- 110 ning solution into the pores, while prevent- 115 ing any of said hides from being bent back over itself and while preventing any of said 120 hides from having one portion come in contact with another portion thereof.

8. The process of tanning which consists in suspending a hide or skin in a tanning solution from the exterior surface of a com- 105 paratively large drum longitudinally of such drum substantially parallel to the axis there- 110 of, and in oscillating the drum to bend the hide or skin in opposite directions with curvatures equal to substantially half of the circumference of the drum and without per- 115 mitting said hide to be bent back over itself or any portion thereof to come in contact with any other portion thereof.

9. The process of tanning which consists in removably attaching several hides at 115 spaced-apart distances on the periphery of a drum of a larger diameter than half the length of the hide, in rotating the drum a number of times in one direction to bend each hide in uniform curvature of not more 120 than a semi-circle and without causing any hide to be bent back over itself or any portion of any hide to come in contact with any other portion thereof, and in alternately 125 reversing the direction of rotation of the drum after a number of rotations in the same direction to secure uniform bending of the hides over approximately semi-circles in

- the opposite direction and to secure separation of the hides temporarily for the flow of the tanning solution between the hides and subsequent overlapping of the hides to cause 5 the latter to press the tanning solution into the pores of the hides opened by such alternate bending.
10. In tanning apparatus, the combination with a receptacle for containing tanning 10 solution, of a comparatively large drum mounted in said receptacle for complete immersion in said tanning solution, means for suspending several hides from the longitudinal exterior surface of said drum in spaced- 15 apart relation when immediately below the drum and overlapping relation when at the sides of the drum, and mechanism for rotating said drum in opposite directions to secure gradual and uniform bending of said 20 hides in opposite directions while immersed in said tanning solution and for securing the overlapping of said hides without causing any of them to bend back upon themselves or over themselves, whereby the tanning solution 25 is pressed into the pores of said hides.
11. In tanning apparatus, the combination with a vat for containing tanning solution, of a cylindrical drum mounted in said vat for complete immersion in said tanning solution, a plurality of rows of screw-eyes arranged longitudinally on the exterior surface of said drum, said rows being spaced-apart circumferentially, a plurality of perforated link devices one pivoted to each of 30 said screw-eyes and adapted to be inserted through U-shaped slits in the hides to be tanned, a plurality of pins, one associated with each of said perforated link devices for securing said hides in suspension from 35 said drum in spaced-apart relation when hanging below said drum and overlapping relation when at the sides of said drum, and means for rotating said drum to secure bending of said hides and overlapping thereof 40 without causing said hides to be bent back upon themselves or over themselves.
12. In tanning apparatus, the combination with a receptacle for containing tanning solution, of a rotatable drum, means for suspending a hide by connecting one end thereof to the exterior of said drum for immersion in said tanning solution, and mechanism for alternately rotating said drum in opposite directions to secure bending of the end 45 tire hide in opposite directions without bending into direct contact with itself or bending over itself.
13. In tanning apparatus, the combination with a receptacle for containing tanning solution, of a rotatable drum mounted in said receptacle, means for suspending several hides by connecting one of the ends of each to the exterior surface of said drum in 50 spaced-apart relation when hanging beneath 65 said drum and in overlapping relation when at the sides of said drum, and automatic mechanism for alternately rotating said drum in opposite directions to secure gradual and uniform bending of all of said 70 hides in opposite directions without any one hide bending back upon itself or over itself, whereby the pores on both sides of each hide are opened and the tanning solution caused to freely wet both surfaces of each hide when said hides are in spaced-apart relation 75 beneath the drum, and whereby said tanning solution is pressed into said pores when said hides overlap and press on each other.
14. In tanning apparatus, the combination with a vat for containing tanning solution, 80 of a plurality of rotatable drums mounted in said vat, means for suspending several hides from each of said drums by connecting one of the ends of each of said hides to the exterior surfaces of said drums in spaced-apart relation when said hides hang below 85 said drums and in overlapping relation when said hides are at the sides of said drums, and mechanism for oscillating said drums simultaneously to secure bending of said 90 hides in opposite directions without bending any one of said hides back upon itself or over itself and to secure the opening of the pores of the hides by the bending, the free flow of the tanning solution over 95 the surfaces of the hides when in spaced-apart relation and the pressure of the tanning solution into the pores when said hides are in overlapping relation.
15. In tanning apparatus, the combination 100 with a vat for containing tanning solution, of a plurality of serially arranged drums mounted in said vat, and means for suspending several hides from each of said drums by connecting one of the ends of each of said 105 hides to the exterior surfaces of said drums in spaced-apart relation when said hides are suspended beneath said drums and in overlapping relation when said hides are at the sides of said drums, and means for oscillating said drums to secure bending of said 110 hides in opposite directions to open the pores thereof and to secure the free flow of tanning solution over the surfaces of said hides and the pressure of the tanning solution into 115 the said pores.
16. In tanning apparatus, the combination with a receptacle for containing tanning solution, of a plurality of spaced-apart parallel hide-supporting drums, interconnected 120 gearing for compelling the drums to rotate either clockwise or anti-clockwise in the same direction; means for suspending several hides from each of said drums in spaced-apart relation when hanging beneath 125 the same and in overlapping relation when

at the sides thereof, and means for oscillating said drums to cause said hides to be bent alternately in opposite directions and overlapped on the same sides of the series of 5 drums alternately.

In testimony whereof I have signed my name to this specification, in the presence of

two subscribing witnesses, on this 29th day of August A. D. 1916.
